UNITED STATES PATENT OFFICE.

EDWARD E. MURPHY, OF WINCHESTER, MASSACHUSETTS, ASSIGNOR TO PUFFER MANUFACTURING COMPANY, A CORPORATION OF MAINE.

DISPENSING-FAUCET.

No. 920,612.

Specification of Letters Patent.

Patented May 4, 1909.

Application filed December 14, 1908. Serial No. 467,413.

To all whom it may concern:

Be it known that I, EDWARD E. MURPHY, a citizen of the United States, residing in Winchester, in the county of Middlesex and State of Massachusetts, have invented an Improvement in Dispensing-Faucets, of which the following description, in connection with the accompanying drawings, is a specification, like letters on the drawings 10 representing like parts.

The present invention relates to a dispensing faucet, and is embodied in a faucet of that class which is used in dispensing carbonated beverages, in which a large outlet nozzle and a small outlet nozzle are employed for mixing purposes.

In accordance with the invention, the faucet is so arranged that the movement of an actuating handle to two different positions 20 in the same direction will open the nozzles respectively, both nozzles being closed when the handle is in its normal position, the valve being preferably provided with a spring whereby it is self closing.

In accordance with the invention, the main or large nozzle is connected directly with the valve chamber which is provided with a lateral inlet and with a longitudinally movable tubular valve provided with 30 lateral inlets and packing to prevent the liquid from leaking around said valve. The small outlet is connected with a supplemental chamber within the large outlet or nozzle, communication between this supplemental chamber and the valve casing being opened by a longitudinal movement of the valve member. The supplemental casing is provided with comparatively large ports through which the liquid can flow to the 40 main nozzle, the construction being such that a complete movement of the valve closes these ports, allowing communication only directly through the small nozzle.

In accordance with the construction, the 45 tubular valve in its first downward movement opens the ports, allowing the liquid to flow into the supplemental chamber, and thence through the outlets to the main nozzle. A further movement of the valve 50 brings the end of the tubular portion thereof to a seat upon a washer located below the ports in the supplemental chamber, the small nozzle opening through the said seat, so that the liquid is free to escape there- 55 from, but has no other outlet.

Figure 1 is a vertical section of a faucet embodying the invention; Fig. 2 is a similar view showing the faucet open to a position to allow the fluid to pass through the large nozzle; and Fig. 3 is a similar view showing 60 the position in which the large nozzle is closed and only the small nozzle is open.

The valve casing *a* which is provided with a lateral inlet *a*², is shown as provided with an arm or extension *a*³ to support a pivotally connected handle *b* connected at *b*² with a tubular valve member *c* which projects into the valve casing *a*. At opposite sides of the inlet *a*², the valve member *c* is surrounded by cup leather packings *d* and *d*², 70 the upper packing being held in position by means of a packing gland *e*, there being also a washer *e*² between the packing and the gland to afford a seat for a spring *f*, the upper end of which bears against a shoulder 75 *c*² formed on the valve member *c*.

As will be seen from the drawings, a downward movement of the valve member *c* causes the spring to be compressed, so that the said spring tends to restore the valve to 80 its normal position shown in Fig. 1 when the handle *b* is released. Below the lower packing *d*² the valve chamber is provided with a main large nozzle *a*⁴ which is shown as screwed into the lower end of the casing 85 *a*, and abutting against the flange *g*² of a supplemental chamber member *g*, which is provided with a small nozzle *g*³, and with comparatively large outlets or ports *g*⁴. The flange *g*² bears against the lower surface of 90 the cup leather packing *d*², and in connection with the nozzle member *a*⁴ affords a packing gland to keep the valve member *c* tight. The said valve member *c* is provided with a longitudinal port *c*³ having a series 95 of lateral inlets *c*⁴ which normally stand above the upper packing member *d* so that the valve chamber is closed by the main wall of the tubular valve. On moving said tubular valve downward, however, the said ports 100 *c*⁴ are brought into communication with the valve chamber, thus allowing the liquid to flow into the tubular portion *c*³. A downward movement of the valve *c*, therefore, to the extent illustrated in Fig. 2, will open 105 communication between the valve chamber and the tubular portion of the valve *c*, allowing the liquid to flow into the supplemental chamber *g*, and thence through the large, lateral ports *g*⁴ to the main nozzle *a*⁴, 110

thus supplying the said main nozzle with a sufficiently large volume of liquid to attain the desired result. The supplemental nozzle g^3 which opens through the bottom of the chamber g will also supply some of the liquid, the said nozzle being opened at this period. In order to cut off the supply from the large nozzle a^4 and to allow the liquid to flow only through the small nozzle g^3 , the device is so arranged that a further movement of the valve c will close communication between the tubular portion thereof and the outlets g^4 , thus allowing the liquid to escape only through the small nozzle g^3 . For this purpose the chamber g is provided at its lower end with a valve seat or washer g^5 against which the end of the valve member c is brought to bear when the valve is moved to the position shown in Fig. 3. This closes communication between the valve member c and the ports g^4 , so that the only path of escape for the liquid is through the small nozzle g^3 .

Since the main source of supply through the valve inlet a^2 is the same for the large and the small nozzles, it is necessary to throttle the small nozzle g^3 to whatever extent is desired, and it may be desirable to afford means for varying the capacity of the said small nozzle. For this purpose, the lower end of the chamber member g above the port which forms the small nozzle may be provided with a screw threaded cup portion g^6 adapted to receive a screw g^7 having a small longitudinal slot g^8 . The capacity of the small outlet, therefore, can be varied by turning the screw to expose more or less of the slot above the top of the cup-portion g^6 .

40 Claims.

1. In a dispensing faucet, a valve chamber provided with a lateral inlet; a tubular valve member longitudinally movable in said chamber, said valve member being packed at opposite ends and provided with lateral ports; a supplemental valve chamber below the main valve chamber, and provided with a small nozzle and relatively large outlets above said nozzle; and a valve seat at the bottom of said supplemental valve member to coöperate with the end of the tubular valve member and close the relatively large outlets, substantially as described.

55 2. In a dispensing faucet, a valve cham-

ber having upper and lower portions; a tubular valve movable in said valve chamber and provided with cut-leather packings, one of said packings being between the upper and lower portions of the valve chamber; a small outlet nozzle opening through the lower portion of the valve chamber which is provided with relatively large outlets above said nozzle; and a valve seat surrounding said nozzle and adapted to coöperate with said tubular valve member to close the relatively large outlets.

3. The combination with a longitudinally movable tubular valve member open at one end and provided with lateral inlets; of a valve chamber having a lateral inlet and being provided with cup-leather packings for said tubular valve member; a supplemental chamber below said valve member provided at the bottom with a small outlet nozzle, and at the sides with relatively large outlet openings; a valve seat surrounding the nozzle at the bottom of said chamber; and means for varying the capacity of said nozzle.

4. In a dispensing faucet, the combination with a casing provided with a lateral inlet and a supporting arm; of an actuating handle pivotally connected with said supporting arm; a tubular valve member projecting through said casing and connected with said actuating handle; a cup-leather packing surrounding the upper end of said tubular member; a spring located between said packing and a shoulder formed on said tubular member; a supplemental chamber portion located below the end of said tubular valve member; a cup-leather packing above said supplemental chamber portion; a large nozzle member extending into the casing and holding said supplemental chamber and said cup-leather packing in position; and a small nozzle within the large nozzle connected with said supplemental chamber which is also provided with a valve seat around said nozzle and with lateral outlets above the same.

In testimony whereof, I have signed my name to this specification in the presence of two subscribing witnesses.

EDWARD E. MURPHY.
